UNITED STATES PATENT OFFICE.

FRANK J. ROWSE, OF PAWTUCKET, RHODE ISLAND, ASSIGNOR TO AMERICAN VENDING MACHINE COMPANY, OF SACO, MAINE, A CORPORATION OF MAINE.

COIN-CONTROLLED VENDING-MACHINE.

SPECIFICATION forming part of Letters Patent No. 743,037, dated November 3, 1903.

Application filed August 20, 1903. Serial No. 170,192. (No model.)

To all whom it may concern:

Be it known that I, FRANK J. ROWSE, a citizen of the United States, residing at Pawtucket, in the county of Providence and State 5 of Rhode Island, have invented certain new and useful Improvements in Coin-Controlled Vending-Machines, of which the following is a specification, reference being had therein to the accompanying drawings.

10 Like numerals indicate like parts.

Figure 1 is a view of my improved coin-controlled vending-machine as seen partly in side elevation and partly in section on line *a a* of Fig. 4. In this figure the coin devices 15 are shown in their position when ready to receive the coin. Fig. 2 is a view of said machine as seen partly in section on line *b b* of Fig. 5, showing the coin devices in their position when the coin has been carried forward 20 and is ready to be released and to drop in the money-drawer. Fig. 3 is a vertical sectional view as seen on line *c c* of Fig. 5 and illustrates the manner in which the package is discharged from the machine and delivered 25 to the purchaser. Fig. 4 is a top plan view of said machine as seen on line *d d* of Fig. 1 when the parts of the machine are in the position shown in Fig. 1. Fig. 5 is a similar top plan view when the parts of the machine 30 are in the position illustrated in Fig. 2. Fig. 6 is a perspective view of the package which is vended. Fig. 7 is an enlarged transverse sectional view of the parts as seen on line *e e* of Fig. 1. Fig. 8 is an enlarged view as seen 35 partly in elevation and partly in section on line *f f* of Fig. 1. Fig. 9 is an enlarged view as seen partly in elevation and partly in section on line *g g* of Fig. 2. Fig. 10 is a top plan view of the coin-carrying devices in the 40 position when a washer substituted for a coin is carried upon the pointed ends of the spring-pressed levers and with the plate of the push-rod in contact with the cam edge of the locking-lever. Fig. 11 is a perspective view of 45 the case of the machine with the lid open to show a portion of the holders of the articles to be vended.

My invention relates to the class of coin-controlled vending-machines; and it consists 50 of the novel construction and combination of

the several parts, as hereinafter described, and specifically set forth in the claims.

In the drawings, 1 represents the box or case inclosing the operative parts of the machine. This box or case rests upon a base 2. 55 The front side has an opening at the bottom, and a drawer 3 is movable therein, as seen in Figs. 1 and 11, by means of a handle 4. A lid or cover 5 is hinged to the top of the case and may be locked, as indicated at 6 in Fig. 60 11. A coin-chute opens at its upper end through a slot 7 in the front side of the case. A push-rod 8 is movable through a round hole in the front side of the case and is operated by a knob 9. 65

The bed of the machine, which supports the mechanism, consists of the horizontal plate 10. The plate 10 has the downwardly-bent projections or flanges 11 12 and is fastened in place by screws 13 14, which pass 70 through said flanges, respectively, into the front side and back of the case, as shown in Figs. 1, 2, and 3. The bed or plate 10 has the aperture 15 (best shown in Fig. 2) and also the two slots 16 and 17. (Best shown in 75 Figs. 2 and 3.)

The coin-chute 18 extends from the slot or opening 7 of the front of the case 1 in a curve or bend and at its lower end terminates in a base 19, which rests at its bottom edge on the 80 bed 10, as seen in Fig. 2. The push-rod 8 is concentrically reduced in diameter, and its smaller or forward end 20 passes loosely through an aperture 21, made therefor in the base 19 of the coin-chute 18. This coin-chute 85 base 19 also has two other perforations or apertures 22 22 through it, arranged in a horizontal line with the aperture 21, which is between them, as seen in Fig. 10.

A plate 23 is mounted fast upon the reduced 90 portion 20 of the push-rod 8 and lies against the shoulder formed by the concentric reduction of said push-rod, as best seen in Fig. 10. As shown in Fig. 7, this plate 23 is semicircular on top and straight on the bottom, with 95 rectangular lower corners, so that its bottom edge slides along the upper surface of the bed-plate 10. A spiral spring 24 surrounds the rod 20. One end of the spring 24 bears against a cross-pin 25, which passes through 100

a diametrical hole in the rod 20, as seen in Figs. 7 and 10, and the other end of the spring 24 bears against the base 19 of the coin-chute.

Two pointed rods or prongs 26 26, which are parallel to each other and to the push-rod 20, are fastened in the plate 23, and the forward pointed ends of said rods 26 26 are movable into and through the holes 22 22 of the base 19 of the coin-chute 18. The usual position of these parts is illustrated in Figs. 1, 4, and 10. As there seen, the spiral spring 24 is in its expanded condition, and the prongs or rods 26 26 are entirely withdrawn from the holes 22 22. A bar 27 extends up from the bed-plate 10 and at its upper end supports the top of the coin-chute 18. The bar 27 has a chamber or depression 28, Figs. 2, 10, and when the push-rod 8 is in its inoperative position the plate 23 is received into said chamber or depression, as shown in Figs. 1, 4, and 5.

The coin-chute 18 has two opposite inwardly-bent flanges 29 29, which narrow at and near their lower ends, leaving a flaring open space there, as illustrated in Fig. 9.

Two levers 30 40 are pivotally mounted on the bed-plate 10 by screws 31 31. (Best seen in Fig. 10.) Each lever 30 has an earpiece 32, and a spiral spring 33 has its ends hook-shaped, one hook engaging with a perforation in one of said earpieces and the other hook engaging with a perforation in the other of said earpieces. Each lever 30 has at its free end a curved jaw or projection 34, nearly ninety degrees in extent and directed inwardly. Normally the outer peripheral edge of each jaw 34, near the center thereof, rests against the adjacent corner of the base 19 of the coin-chute 18.

A locking-lever 35 is pivotally mounted on a screw 36, which enters the bed-plate 10. It has the upward bend 37 (indicated at 37) and also the lateral curve 38. The inner peripheral edge 39 of said curve constitutes a cam-surface, against which the edge of the plate 23 is adapted to contact. The opposite end of the locking-lever 35 is provided with three notches or serrations 40. A spiral spring 41 has one end thereof hooked into a hole 42 of the lever 35 and its opposite end hooked into a perforated stud 43, which is set in the bed-plate 10. The lower portion of the bar or plate 27 is cut away, as shown at 44 in Fig. 7, to allow the movement of the locking-lever 35, which at that place is bent up to lie above the adjacent lever 30 and its pivotal screw 31. The curved end of the locking-lever 35 lies in the chamber 28, as indicated in Figs. 4 and 5, but more plainly seen in Fig. 10.

At the bottom of the coin-chute 18 are two bent lips or projections 45 45, upon which the coin 46 is supported.

The bed-plate 10 has an upwardly-directed flange 47, which is slotted, as indicated in Fig. 2. A sliding plate 48 rests upon the bed-plate 10 and is movable through said slot. The end of the sliding plate 48 toward the front of the machine is upturned and provided with an

aperture, as seen in Fig. 2. Said sliding plate 48 has a longitudinal slot 49. A stud or pin 50, fixed in the bed-plate 10, projects up through the slot 49 of the sliding plate 48.

A feed-lever 51 is pivotally mounted on a screw 52, which extends into the bed-plate 10. The lever 51 has a slot 53 at one end and a slot 54 at its opposite end. It is also provided with an upwardly-bent lip 55. A spiral spring 56 has one end thereof hooked through a hole in the flange 47 of the bed-plate 10 and its opposite end hooked through a hole 57 in the feed-lever 51. The lever 51 is adjustably mounted on a screw-pivot 58, which is shouldered, as seen in Fig. 2, and screwed into the sliding plate 48.

Two vertical holders 59 59 are provided, each of which has two parallel sides and also flanges 60 60. They are secured in position by screws 61, which pass through the flanges 60 into the bed-plate 10. The vendible article is in the form of a package 62. (Shown separately in Fig. 6.) These packages are piled up, with their ends projecting loosely in the holders 59, and a weight 64 is placed upon the top of the pile, as shown, to press them down.

The holders 59 59 have the slots 64 and 65, the bottoms of which are even with the upper surfaces of the bed-plate 10, as seen in Fig. 3.

In the slot 16 of the bed-plate 10 is the slide 66, whose upper side rests upon the top of said bed-plate and whose lower side lies against the under surfaces of said bed-plate, as seen in Figs. 3 and 4. From the lower side of the slide 66 a pin 67 projects, which extends through the slot 53 of the feed-lever 51. The slide 66 is movable along the slot 16 of the bed-plate 10 and the slot 65 of the holder 59.

The sliding plate 48 has a downwardly-extending earpiece 68, which moves along the slot 17 of the bed-plate 10 and confines the sliding plate 48 to a linear movement.

The feed-lever 51 on the part adjacent to the sliding plate 48 lies above the bed-plate 10, but has a bend, as indicated at 69, and there passes down through an opening 70, so that the free end of the lever 51 is beneath the bed-plate 10, as illustrated in Figs. 4 and 5.

Having thus described the several parts of my invention, I will now explain the operation.

The normal position of the parts is that shown in Figs. 1, 4, and 11. A coin 46 is inserted through the opening 7 and descends by gravity down the coin-chute 18. When the coin 46 reaches the bottom of the chute 18, it rests upon the two projecting lips 45 45, as seen in Figs. 4, 8, and 9. At this time the peripheral edges of the jaws 34 rest against the edge of the coin 46, as seen in Figs. 4 and 9. The operator then presses against the knob 9, and so moves the push-rod 8 20 from the position shown in Figs. 1

and 4 to the position shown in Figs. 2 and 5. By this inward movement given to said push-rod the pointed rods or prongs 26 26 enter and pass through the holes 22 22 of the base 19 of the coin-chute, and the reduced end 20 of the push-rod passes through the hole 21, Fig. 8, of said base 19, and the spiral spring 24 is compressed. The sharp point of the push-rod 20 bears against the 10 coin 46 at the center thereof and presses said coin against the upturned flange of the sliding plate 48, as illustrated in Figs. 2 and 5. At the same time, the pointed rods or prongs 26 26, fastened to the plate 23 of the push-rod 8 20, move forward with said push-rod, enter and pass through the holes 22 22 made therefor in the base 19 of the coin-chute. As 15 the coin 46 thus moves forward it spreads apart the jaws 34 34 of the lever-arms 30 30 until it has passed the same, whereupon by 20 force of the spring 33 said lever-arms 30 30 are drawn toward each other, and the sharp ends of the jaws 34 34 move inwardly to the 25 position illustrated in Fig. 10. In this manner the sliding plate 48 is caused to slide or move inwardly, being kept to a direct line of movement by means of the pin or stud 50 of the bed-plate 10 in the slot 49 and the ear 68 in the slot 17 of said bed-plate. This inward travel of the sliding plate 48 results in 30 the movement of the feed-lever 51 from the position shown in Fig. 4 to the position shown in Fig. 5. As the free end of the lever 51, which, as seen in Fig. 4, is wholly outside of 35 the holder 59, moves toward the front of the machine the slide 66 is pushed along the slot 16 by reason of the projection of the pin 67 of the slide 66 through the slot 53 of the feed-lever 51, and so the slide enters and passes 40 through the slot 65 of the holder 59 (see Fig. 3) and pushes out the lowermost package 62 of the pile of vendible articles, which package 62 so pushed passes out through the slots 64 of the opposite holder 59, when its projecting end can then be seized by the operator 45 and withdrawn from the case, as indicated in Figs. 3 and 5. As the feed-lever 51 moves, as above described, from the position shown in Fig. 4 to the position shown in Fig. 5 the lip 55 of the lever 51 moves by its beveled edge along the serrations or notches 40 of the locking-lever 35, said serrated portion of the lever 35 being held in contact with the lip 55 of the lever 51 by the force of the spiral 50 spring 41. Whenever the lip 55 is engaged with either one of the notches 40 of the lever 35, the sliding plate 48 is prevented from a reverse movement. The consequence is that 55 as soon as the operator ceases to press against the knob 9 of the push-rod 8 and said rod is free to return to its normal position by force of the spiral spring 24 the sharp point of the reduced end 20 of the push-rod 8 moves away from the coin 46, (which it has hitherto kept 60 by its pressure in contact with the upturned end of the sliding plate 48,) and the coin 46 being no longer supported falls by its gravity

and drops into the drawer 3 beneath it. As the push-rod 8 returns to its normal position when allowed by force of the spiral spring 24 70 the plate 23, which is fastened upon said rod, moves with it, and the edge of said plate 23 coming into contact with the cam edge 39 presses against and moves the locking-lever 35 in the direction of the arrow in Fig. 10 75 from the position shown in Fig. 10 to the position shown in Fig. 1, where it is seen that the end of the lever 35 rests against the edge of the plate 23. The return movement of the push-rod 8 20 is given by the spring 24, the 80 return movement of the sliding plate 48 is given by the spring 56, and the return movement of the feed-lever 51 is given by the spring 56.

The purpose of the serrations 40 of the locking-lever 35 and the engagement of the lip 55 of the feed-lever 51 therewith is to enable the release and fall of the coin. By this contrivance the sliding plate 48 is prevented from following the push-rod 8 20 in its return 90 movement.

My improved vending-machine is provided with devices by which the use of metallic washers or pasteboard counters intended to be fraudulently used instead of coin is prevented. In case a metallic washer 46^a is used instead of a coin the action is as follows: The point of the push-rod 20 passes freely through the central aperture of such washer into the opening 71 of the upturned edge of 10 the sliding plate 48 and effects no result whatever. The continued pressure upon the knob 9 advances the prongs or rods 26 26 and causes them to move through the openings 22 22 of the base 19, Fig. 10, and to press 105 against the washer near the rim thereof. (See Fig. 9.) Thus the washer is pushed by said rods or prongs 26 26 from the position shown in Fig. 4 to the position shown in Fig. 10 and is crowded out past the curved jaws 110 34 34 of the levers 30 30. The washer then lies between the sharp points of said jaws and the upturned end of the sliding plate 48. In this manner the space is cleared for the reception again of a coin, and yet the article 115 to be delivered has not been delivered. The washer remains in this position until a coin has been put into the coin-chute 18 and has been operated upon in the usual manner, as hereinbefore described. If, however, another 120 washer is put in instead of a coin, the second (or any subsequent) washer is disposed of the same as the first. Whenever a coin is put in after a washer, the coin is pushed forward by the push-rod. It is pressed into contact with said washer instead of being pressed into contact with the upturned end of the sliding plate 48, and all three—the coin, washer, and sliding plate—are moved inwardly; but as soon as the feed-lever 51 and the locking-lever 35 are fastened together by the lip 55 in some one of the notches 40 and the operator removes his hand from the knob 9 both the washer and the coin drop together 125 130

by gravity into the drawer beneath. Thus the use of a metallic washer is ineffectual to secure a delivery of a package 62 by the machine.

5 Suppose that instead of a coin 46, as illustrated in Fig. 4, a pasteboard disk is used which has the same diameter as the coin. When inserted in the slot 7, it will, like the coin, slide down the chute and rest upon the 10 lips 45; but as the end of the reduced portion 20 of the push-rod 8 has a sharp thrusting-point said point when the knob 9 is pressed inwardly to move the push-rod penetrates and passes through such pasteboard disk, the 15 hole 71 in the upturned end of the sliding plate 48 allowing this thrusting movement and receiving the sharp point of the push-rod after it has passed through the pasteboard disk. For this reason the sliding plate 20 is not forced inwardly, whereas in case a coin is used, as hereinbefore explained, the coin covers the aperture 71, and the thrust of the point of the push-rod is centrally received and resisted by the coin, so that the 25 pressure of said point against the coin causes the coin to press against the upturned end of the sliding plate 48, and thus the sliding plate 48 is moved inwardly; but as the pasteboard disk is not pushed but pierced by the point of 30 the push-rod the sliding plate 48 is not moved. The continued pressure upon the knob 9 causes the push-rod 8 20 to move inwardly still farther, and so the two pointed rods or prongs 26 26 move to and through the openings 22 22 made therefor in the base 19 of the 35 coin-chute 18. The points of the rods or prongs 26 then come in contact with the pasteboard disk and push it off from the lips 45 45, and so clear it from the chute 18 and beyond 40 the jaws 34 34, as shown in Fig. 10. When the three pointed rods 20, 26, and 26 when the pressure on the knob 9 ceases are withdrawn by the spring 24 to the position shown in Fig. 1, the pasteboard disk is no longer supported, 45 but drops into the drawer 3 beneath through the space between the coin-chute and the upturned end of the sliding plate 48. It will be observed that the edges of the upturned end of the sliding plate 48 are beveled, so that 50 said upturned end is capable of entering between the ends of the jaws 34 34 and to approach the coin-chute to a proper distance.

I claim as a novel and useful invention and desire to secure by Letters Patent—

5 1. In a coin-controlled vending-machine, the combination of a coin-chute with means to support a coin at the lower end thereof, a spring-pressed push-rod supported in and movable through an aperture in the coin-chute, a sliding plate properly mounted and having an upturned edge adapted to contact with and receive pressure from said coin when the latter is pressed by the push-rod, a feed-lever properly mounted and pivotally connected at one end with said sliding plate and provided with a lip, a locking-lever properly mounted and provided with a notch with

which said lip of the feed-lever is engageable, a spring to give return movement to the feed-lever, a spring to give return movement to the locking-lever, means intermediate said push-rod and locking-lever to operate the latter from the former for the purpose of disengaging the locking-lever from the feed-lever, a holder or receptacle having slots in its sides at its bottom and adapted to hold a vendible package, and a slide pivotally connected with the feed-lever and adapted to move said package out of said holder or receptacle, substantially as described. 60

2. In a coin-controlled vending-machine, the combination of a coin-chute with means to support a coin at the lower end thereof, a push-rod supported by and movable through an aperture in the coin-chute and provided 85 with a plate mounted thereon, a sliding plate properly mounted and having an upturned edge adapted to contact with and receive pressure from said coin when the latter is pressed by the push-rod, a feed-lever properly mounted and pivotally connected at one end with said sliding plate and provided with a lip, a locking-lever properly mounted and provided with a notch with which said lip of the feed-lever is engageable and having a cam edge 95 with which the plate of the push-rod is adapted to contact, a spring to give return movement to the push-rod, a spring to give return movement to the feed-lever, a spring to give return movement to the locking-lever, a holder 100 or receptacle having slots in its sides at its bottom and adapted to hold a vendible package, and a slide pivotally connected with the feed-lever and adapted to move said package out of said holder or receptacle, substantially 105 as specified.

3. In a coin-controlled vending-machine, the combination of a pivotally-mounted lever, a slotted bed-plate, a slide movable in said slot and connected with one end of said lever, a 110 sliding plate movable in another slot of said bed-plate and pivotally connected with the opposite end of said lever, a push-rod, a slotted receptacle for a vendible package, automatic means of locking said lever in either 115 of several positions which means are operated from the push-rod on its return movement, and means for giving return movement to the push-rod and to said lever, respectively, substantially as described. 120

4. In a coin-controlled vending-machine, the combination of a coin-chute having coin-supports at its lower end, a push-rod capable of movement by hand in an inward direction and of an outward movement by a spring, a 125 plate or bar mounted on said push-rod, two rods mounted on said plate or bar parallel with the push-rod and with each other, and a base for said coin-chute provided with three openings or holes into and through 130 which said push-rod and said two other parallel rods respectively are movable, substantially as and for the purpose specified.

5. In a coin-controlled vending-machine,

the combination of a coin-chute having coin-supports at its lower end, a push-rod having a sharp-pointed end, a spring to give reverse movement to the push-rod, a plate or bar on the push-rod, a base for said coin-chute having three openings or holes therethrough, two rods or prongs provided with sharp-pointed ends and mounted on said plate or bar parallel with the push-rod so that said three rods are movable into and through the three holes respectively of the coin-chute base, a sliding plate having an upturned end which has a perforation adapted to receive the end of the push-rod, and a spring to give return movement to said sliding plate, substantially as described.

6. In a coin-controlled vending-machine, the combination of a coin-chute having coin-supports at its lower end, a push-rod, a spring

to give reverse movement to the push-rod, a plate or bar on the push-rod, a base for the coin-chute having three openings or holes therethrough, two rods or prongs mounted in said plate or bar parallel with the push-rod so that said three rods respectively are movable into and through the three holes respectively of the coin-chute base, two levers each pivotally mounted at one end thereof and having at the opposite end a curved jaw, and a spring connecting said two levers, all arranged and operating substantially as shown and for the purpose specified.

In testimony whereof I affix my signature in presence of two witnesses.
